UNITED STATES PATENT OFFICE.

ARMAND H. PEYCKE, OF CHICAGO, ILLINOIS, ASSIGNOR TO AMERICAN STEEL FOUNDRIES, OF CHICAGO, ILLINOIS, A CORPORATION OF NEW JERSEY.

METHOD OF MAKING FORGED FULCRUMS.

1,283,887.

Specification of Letters Patent.

Patented Nov. 5, 1918.

Application filed April 5, 1918. Serial No. 226,910.

To all whom it may concern:

Be it known that I, ARMAND H. PEYCKE, a citizen of the United States, and resident of Chicago, in the county of Cook and State of Illinois, have invented certain new and useful Improvements in Methods of Making Forged Fulcrums, of which the following is a specification.

This invention relates to a method of forming a steel fulcrum.

The object of this invention is to simplify and improve the method of making a forged steel fulcrum and at the same time minimize the cost thereof.

This and other objects are accomplished by employing the method consisting first in providing a blank having a web and flanges, then forming a brake lever opening in the web, then forming the flanges at one end of the blank into a shape to coöperate with a brake beam compression member, and then forming a seat in the other end of the blank for the reception of a tension member.

The invention is illustrated on the accompanying sheet of drawings in which:

Figure 1 is a plan view and Fig. 2 an end view of a blank.

Fig. 3 is a plan view, showing a blank as provided with a perforation through the web thereof and a portion of the web removed at the end thereof.

Fig. 4 is a plan view of the blank after the flanges at one end have been pressed into a lateral position and the intermediate portion of the blank pressed to form side walls for the central opening.

Fig. 5 is a sectional view taken in the plane of line 5—5 of Fig. 4.

Fig. 6 is a plan view of the fulcrum, after one end thereof has been provided with a tension rod seat.

Fig. 7 is an end view of the fulcrum.

Fig. 8 is a plan view of the completed fulcrum after the central body portion thereof has been twisted 40° with respect to the ends of the fulcrum.

Fig. 9 is a sectional view, taken on the plane of line 9—9 of Fig. 8.

Fig. 10 is a fragmentary side elevation of a modified form of fulcrum for the reception of a brake beam compression member, and

Fig. 11 is a transverse sectional view of a modified form of fulcrum.

The various novel features will be apparent from the following description and

drawings and will be particularly pointed out in the appended claims.

Referring to the figures of the drawings, it will be noted that I have provided a blank 15 in the form of an H-bar having a central web 16 and associated flanges 17 and 18.

In forming this brake beam fulcrum the first step taken is to punch out some of the metal in the central portion of the web 16 to form an opening 19 for the reception of a brake lever. At the same time one end of the web 16 is punched away to leave two arms 20 and 21, which in the next operation are pressed laterally into a position at right angles with respect to the body of the blank 70 for securing the latter to the compression member of a brake beam. During the same operation the flanges 17 and 18 are pressed inwardly toward each other forming a depression intermediate the ends of the bar 75 and at the same time providing side walls for the opening 19 in which are forged extended bearing projections 22 and 23, which are recessed a predetermined amount, as shown at 24. During the next operation one end of the blank is treated by suitable dies 80 to provide a seat 25 for the reception of a brake beam tension rod, as shown in Figs. 6 and 7, after which the central body portion of the fulcrum is twisted at an angle of 40° 85 with respect to the ends of the fulcrum, as shown in Figs. 8 and 9. The fulcrum is completed by drilling or punching openings 26 in the arms 20 and 21, whereby the latter may be secured to the brake beam compression member. Holes also are drilled or punched at 27, as shown in Figs. 8 and 9 for the reception of a brake lever pin therein.

If desired, one end of the fulcrum may be provided in the form of a band 28, as shown in Fig. 10, for embracing the compression member 29 instead of securing the arms 20 and 21 to the compression member by rivets.

Also instead of pressing the intermediate portions of the flanges 17 and 18 bodily toward each other, as shown in Figs. 4 and 6, the edges 30 of the flanges may be turned inwardly toward each other for forming lateral supporting portions for the brake 105 lever.

It will be appreciated that during these operations the metal is heated to the proper temperature to facilitate the operations.

It is my intention to cover all modifica- 110

tions of the invention falling within the spirit and scope of the appended claims.

I claim:

1. The method of forming a forged fulcrum, consisting first in providing a blank having a web and flange, then perforating the web for the reception of a brake lever and removing another part of the web to form an arm of a portion of the flange to co-operate with the brake beam compression member, and then providing one end of the blank with a seat for a tension member.
2. The method of forming a forged fulcrum, consisting first in providing a blank having a web and flange, then perforating the web for the reception of a brake lever and removing another part of the web to form an arm of a portion of the flange to co-operate with the brake beam compression member, then providing one end of the blank with a seat for a tension member, and then giving the intermediate portion of the fulcrum and the ends thereof a relative twist.
3. The method of forming a forged fulcrum consisting first in providing an H shaped bar having a web and flanges, then punching out portions of said web to form an opening for a brake lever and for forming arms to co-operate with a brake beam compression member, and then forming a seat in one end of the blank for the reception of a tension member.
4. The method of forming a forged fulcrum consisting first in providing an H shaped bar having a web and flanges, then punching out portions of said web to form an opening for a brake lever and for forming arms to co-operate with a brake beam compression member, then forming a seat in one end of the blank for the reception of a tension member, and then twisting the central part of the fulcrum at an angle with respect to the ends of the fulcrum.
5. The method of making a forged fulcrum consisting first in providing an H shaped blank having a web and flanges, then removing portions of the web to form an opening for the reception of a brake lever and for forming arms of the flanges at one end of the blank for co-operation with a compression member, then pressing the flanges of the blank intermediate the ends thereof for forming walls for the lever opening, and then forming a tension rod seat in one end of the blank.
6. The method of making a forged fulcrum consisting first in providing an H shaped blank having a web and flanges, then removing portions of the web to form an opening for the reception of a brake lever and for forming arms of the flanges at one end of the blank for co-operation with a compression member, then pressing the flanges of the blank intermediate the ends thereof for forming walls for the lever opening, then forming a tension rod seat in one end of the blank, and then twisting the middle portion of the blank at an angle with respect to the ends thereof.
7. The method of making a forged fulcrum consisting first in providing an H shaped blank having a web and flanges, then removing portions of the web to form an opening for the reception of a brake lever and for forming arms of the flanges at one end of the blank for co-operation with a compression member, then pressing the flanges of the blank intermediate the ends thereof for forming walls for the lever opening, then forming a tension rod seat in one end of the blank, then twisting the middle portion of the blank at an angle with respect to the ends thereof, and then providing the walls of the lever opening with holes for a brake lever pin and providing the arms with holes for securing said arms to the compression member.

Signed at Chicago, Illinois, this 28th day of March, 1918.

ARMAND H. PEYCKE.
